CARL J. OLSON, OF MINNEAPOLIS, MINNESOTA

PROCESS FOR MAKING GLASS SIGNS

Application filed April 16, 1930. Serial No. 444,701.

This invention relates to processes for making glass signs.

At the present time there is a large demand for glass signs. These signs are usually made by sign painters having a high degree of skill in the art of lettering and figure and design painting. The outline of the complete design for the sign is usually first laid out on the rear side of the glass in reversed relation, whereupon the sign painter fills in the complete design directly on the glass by paint, metal leaf or the like. All the work is hand work and, of necessity, the border lines between one individual design and a second individual design in a composite design cannot be made with absolute accuracy. The nicety of the sign depends entirely on the degree of skill of the particular artisan doing the work. As a rule, the border lines between one individual design in a composite design and another individual design in the composite design are not sharp and clear and the individual designs in a composite design will not stand out clearly from each other.

It is an object of the present invention to provide processes for making glass signs, whereby the signs can be made with extreme accuracy and in much shorter time than is usually required in making similar glass signs today, without necessitating the exercise of a high degree of skill on the part of the sign painter.

It is a further object to provide improved processes for making composite design glass signs, whereby the borders between individual designs in the composite design sign will be absolutely true and accurate and, as a result, the individual designs will clearly stand out from each other to present a much more striking appearance than is the case in the usual glass sign made today.

To these ends, the invention consists in the novel processes and the novel steps in the processes hereinafter defined in the claims and described in the following specification, made in connection with the accompanying drawings, wherein like reference characters refer to the same or similar parts throughout the various views and, in which,

Fig. 1 is a view in front elevation illustrat-

ing a complete glass sign made by use of the processes of my invention;

Fig. 2 is a view illustrating a stencil that may be used in producing the sign shown in Fig. 1;

Fig. 3 is a view showing the rear side of the sign when certain steps in the process of making the sign have been completed;

Figs. 4, 5 and 6 are sectional views taken on the lines 4-4, 5-5 and 6-6 respectively, of Figs. 1, 2, and 3, and

Figs. 7, 8 and 9 are perspective sectional views showing a certain portion of the sign illustrated in Fig. 1 during different steps of its construction.

Although practically any type of glass sign can be made by use of my present process and processes, I have shown in the drawings a particular sign which is illustrative of various types of signs that may be made by use of my present process and processes and I will describe my process and processes in connection with the construction of the sign illustrated.

The glass sign illustrated in Fig. 1 is a composite design sign including a plurality of individual designs. The letter "R" design 10 is composed of gold leaf and is divided into two parts, the part 10a and the part 10b, the part 10a being bright and unshaded and the part 10b being shaded to give a dull or rough effect thereto to produce the effect of three dimensions in the design 10. To make the design 10 stand out, a background design 11 is used and this background is illustrated as being of green color. A second background design 12 surrounds the design 11 and this second background design is shown as being of blue color. Another design 13 illustrated as being of red color surrounds the design 12 and serves as a border design to contrastingly set off the other designs of the sign.

My process and processes for making the sign illustrated in Fig. 1 may be described as follows:

A stencil 14 is first prepared having the reverse outlines of the parts 10a and 10b of design 10 and designs 11, 12 and 13 defined thereon by perforations 14a. The stencil may be made in any desired manner on prac-

tically any type of sheet material, but will preferably be made by drawing the reversed outlines of the various individual designs and the parts of the design 10 thereon by pencil, whereupon the perforations 14a may be punched through the sheet material.

The glass upon which the sign is to appear is designated by the numeral 15. Preparatory to making the sign, the back side of this 10 glass will be thoroughly cleaned, whereupon the entire back of the glass will be moistened with water, so that a thin layer of water lies completely over the back side of the glass. A thin layer of metal foil 16, such as tinfoil, is 15 then spread on the water completely over the back of the sign, the water permitting the tinfoil to be spread evenly and also acting to hold the tinfoil in place. Preferably, the foil 16 will be smoothed evenly on to the 20 glass as by means of a roller or the like. After the foil 16 is in place on the glass 15, the stencil 14 will be applied over the back side of the foil 16, whereupon a powdered material such as powdered chalk or powdered charcoal contrasting in color with the 25 foil 16, will be worked through the perforations 14a of the stencil to cause the stencilled outlines of the various individual designs in the composite design to appear on the back 30 of the foil 16 in reverse relation. Preferably the powdered material will be worked through the perforations 14a of the stencil by shaking a small cloth strainer bag, carrying the powdered material, over the perforations 35 14a of the stencil.

The outlines of the individual designs are now cut through the foil 16 to the glass 15 by means of a sharp knife or the like, by following the stencilled outlines of the individual 40 designs as imprinted on the back side of the foil 16. In Figs. 3 and 6, the cut foil applied to the glass 15 is illustrated, the cuts in the foil being designated by the numeral 45 17. After the cuts 17 are made, the cut edges of the foil 16 will be pressed downwardly 50 against the glass 15 as by applying a paper over the foil 16 and pressing inwardly on the paper over the cuts 17. As the cuts 17 will be made with a sharp knife, or similar 55 sharp tool, and as the foil 16 is an easily cut material, the outlines of the various designs may be cut through the foil 16 with extreme accuracy, it being possible to use a straight edge along which the knife may be guided for

The next step in my process is to remove 60 from the glass 15 those portions or strips of foil 16 which overlie the portions of the glass upon which the shaded parts 10a of the 65 sign 10 are to appear, while allowing all other parts of the foil 10 to remain in place on the glass. In Fig. 7, a sectional perspective view of a portion of the sign completed as thus far described, is illustrated, 70 the strips of foil 16 covering that portion of

the glass 15 where the shaded part 10b of the design 10 is to appear, being removed. The space left by removal of the strips of foil over the portion of the glass to be covered by the shaded part 10b of the design 10 is now 75 filled in by varnish 18, or similar transparent material, and the varnish 18 or the like is allowed to dry. The foil 17 adjacent the portion of the glass to be filled in by the shaded part 10b of the design 10 will act to prevent the varnish 18 from being spread onto other portions of the glass and as a result no great care must be exercised in applying the varnish 18, it being immaterial whether part of the varnish overlaps some of the foil 16 or not. The varnish 18 can, therefore, be very quickly applied to the glass and the edges of the varnish layer applied to the glass will be absolutely true and accurate. In Fig. 8, the varnish 18 is shown as applied to the glass 15. 80

After the varnish 18 has hardened, strips of foil 16 adjacent the varnish and covering that portion of the glass where the unshaded parts 10a of the design 10 are to appear, will be removed. If desired, portions of the varnish 18 may be scraped off the glass to produce the shade lines 19 at certain points in the part 10b of the design 10. Gold leaf 20 as shown in Fig. 9, will now be applied over the varnish layer 18 and over the glass 15 to 90 completely cover the space on the glass to be taken up by the complete design 10. No particular care need be exercised in applying the gold leaf 20 inasmuch as portions of the leaf may overlap portions of the foil 16 placed over portions of the glass where the design 11 is to appear. The gold leaf 20 will be applied in the usual manner as by a fine brush, a thin glue being used to secure the leaf to the 95 glass 15 and the varnish 18. 100

The foil overlying portions of the glass 15 where the design 11 is to appear will now be removed from the glass by ripping the same off from the glass and as this foil is removed, any portions of the gold leaf 20 which overlie these portions of the foil, will be broken sharply off due to the fact that the leaf 20 is extremely thin. The edges of the design 10 will be clearly defined by the gold leaf 20 110 with extreme accuracy. 115

The design 11 may now be filled in on the glass with green paint and no great care need be used in applying the paint as it makes no difference whether or not the paint will overlap the gold leaf 20 and the foil 16 overlying that portion of the glass where the design 12 is to appear. The foil overlying the portion of the glass where the design 12 is to appear may then be removed after the paint or other material forming the design 11 has dried, whereupon the design 12 can be filled in in the space left on the glass with blue paint or the like. After the design 12 has been applied and the paint thereof dried, the remaining portions of the foil 16 on the glass may 120 125 130

be removed and the free portions of the glass filled in with the red paint forming the design 13.

As, whenever any individual design in the composite design is filled in on the glass, all other portions of the glass will be covered by either the foil 16 or by an individual design already filled in, it will be seen that the edges of the design being filled in can be made with extreme accuracy and that the lines between adjacent designs will be true and clear cut. As a result, the individual designs in the composite design will stand out from each other distinctly. There will be no merging of one individual design into another individual design and no great care need be taken at the time that the paint, metal leaf or the like, for any individual design, is applied to the glass.

As was stated, the design illustrated is merely illustrative of the type of work that can be done by use of my process and processes. It is perfectly possible to make practically any type of glass sign by use of my process and processes. For example, in the sign illustrated, if it is desired to eliminate the design 11 and permit the letter design 10 to appear in outline on transparent glass, the foil 16 covering the space on the glass where the design 11 appears during the manufacture of the sign, may be allowed to remain in place until all other designs on the sign are filled in, whereupon the foil may be removed from the glass to cause the letter "R" to stand out in relief from the transparent glass. Any portion of the sign may be filled in with gold or silver leaf or any portion of the sign may be filled in with paint, varnish or similar substance to produce the desired appearance in the sign. The foil 16 may be common tinfoil, lead foil, or any other similar metal foil. In place of using a stencil 14, the outline of the complete design may be applied to the foil 16 in any desired manner. The sequence in which varnish designs in a composite design are applied to the glass, may be varied at will.

The time required in producing a glass sign by use of my present process and processes is found to be a great deal less than the time that must be used in producing a similar type sign under present methods. The reason that my glass sign can be produced so quickly is largely due to the fact that no care need be exercised at the time any particular design is being filled in on the glass. As best shown in Fig. 4, the paint, metal leaf etc. forming the various designs may be allowed to overlap on the rear sides of designs previously applied to the glass or to overlap on the metal foil strips and no care need be exercised in producing the edges of the various designs as is the case in the ordinary glass sign made today.

My process and processes have been successfully demonstrated in actual practice and

the work produced has been extremely satisfactory.

It will, of course, be understood that various changes may be made in my processes and the various steps therein without departing from the scope of the present invention.

What is claimed is:—

1. The process of making a shaded metal leaf design glass sign, which consists in applying metal foil to the back of the glass upon which the sign is to appear, cutting the outlines of both the shaded and unshaded portions of the design to be reproduced in metal leaf through the metal foil to the glass, removing, from the glass, strips of metal foil which cover portions of the glass to be filled in by the shaded portions of the metal leaf design, processing the glass in the spaces left therein by withdrawal of said strips to produce the desired shading effect when metal foil is applied over said open portions of the glass, removing, from the glass, strips of the metal foil covering those portions of the glass that are adapted to be filled in by the unshaded portions of the metal leaf, filling in the open portions of the glass produced by removal of said first mentioned and second mentioned metal foil strips with metal leaf and then removing the metal foil about the metal leaf design.

2. The process defined in claim 1, and filling in the portions of the glass about the metal leaf design with a background design.

In testimony whereof I affix my signature.

CARL J. OLSON.
